DISPLAY DEVICE

George E. Buzzu, Los Angeles, Calif.

Application December 11, 1939, Serial No. 303,648

3 Claims. (Cl. 312—120)

This invention relates to a display device.

In the merchandising of various goods and particularly such items of merchandise as greeting cards and gift cards it is desirable to display the cards so that the faces of the cards may be easily read and so that the cards may be conveniently removed from a supporting rack without disturbing the other cards in the rack. It is also desirable to provide storage spaces directly associated with the cards being displayed whereby additional cards of a particular type or number may be instantly obtained in the event that they are required either for replenishing the display stock or filling an order. It is the principal object of the present invention, therefore, to provide a display rack which will present a large number of cards to view, insuring that the front faces of the cards may be completely legible without removing them from the rack, and further providing means whereby storage compartments may be quickly opened adjacent to a particular card so that other cards may be obtained, at the same time insuring that when the compartments are closed the rack will be restored to its original slightly appearance.

The present invention contemplates the provision of a rack supporting a plurality of display shelves superimposed one upon the other and mounted so that the goods displayed upon them will not obstruct the view on any part of the rack, the structure being further provided with pivotal mountings for the shelves whereby the separate shelves may be swung to a position affording access to storage compartments in the rear thereof.

The invention is illustrated by way of example in the accompanying drawing, in which:

Figure 1 is a view in vertical elevation showing the rack embodying the features of the present invention.

Fig. 2 is a view in central vertical section through the rack showing the arrangement of the various shelves and compartments.

Fig. 3 is an enlarged view in vertical section showing the shelf construction and the manner in which the shelves move to disclose a storage compartment.

Referring more particularly to the drawing, 10 and 11 indicate the side walls of the rack of which the present invention is concerned. These side walls are substantially in the shape of right-angle triangles. Their bottom edges receive a floor 12 upon which the structure rests and the vertical back edges of the sides receive a back wall 13. This wall is removable in part. A hori-

zontal molding 14 is disposed across the top of the back wall 13 and from one side wall to the other for a purpose to be hereinafter described, and a vertical facing board 15 is disposed across the forward edge of the bottom wall 12 and from one side wall to the other. The forward edges of the sides 10 and 11 are inclined at substantially 45 degrees to the horizontal face and shelf structures 16 are disposed between the sides 10 and 11 and are arranged in graduated spaced relation the length of the inclined edges of the side wall and between the two side walls since it is desirable that the shelves be of different height to accommodate merchandise of different dimensions. These shelf structures, as more particularly shown in Fig. 3 of the drawing, comprise a floor 17 which receives pivot pins 18 extending in from the side walls and engaging the members so that they will swing. Attention is directed to the fact that as arranged the floors 17 are disposed at an angle to the edge 19 of the side walls, which angle is less than a right angle. Secured to the backs of the floor members 17 are back panels 20 which are disposed at right angles to the plane of the floors. These back panels extend upwardly and their upper edges terminate directly beneath the lower forward edges of the floor 17 of the next succeeding shelf structure. Extending at right angles to the floor 17 and along the front edge thereof is a strip 21 which is held by a hook-shaped clip 22. This clip is secured in position by screws 23. The strip 21 is here indicated as being made of glass so that the visibility of the lower portion of the merchandise will not be impaired. Secured to the side walls 10 and 11 and in the same plane normally assumed by the floors 17 of the shelf structures 16 are stop or guide strips 24. The forward edges of these strips, as indicated at 25, provide an abutment for the rear edges of the floor members 17. This will limit the rearward swinging movement of the shelves from an aligning position. The upper faces 26 of the strips 24 provide guide faces and supports for the back element 27 of a compartment, which includes a floor 28. The floor 28 is hinged to the back panel 20 of a shelf structure 16 by the hinge 29 and is free to swing toward a position of alignment with the back panel 20 when the back panel is drawn forwardly, as will be hereinafter described. Finger holds 30 are formed in the back panel to facilitate in drawing the panel forwardly. Disposed adjacent to the uppermost shelf 16 is a compartment 31 formed by a floor 32 and a wall

panel 33. This compartment is accessible when the uppermost shelf 16 is drawn forwardly.

In operation of the present invention cards 34 may be placed upon the shelf units with their lower edges resting upon the floor 17 while they are supported in an inclined position while leaning against the back walls 20 of the shelves. The space upon the members 28 and between the back walls 20 and the rear compartment members 27 are of such dimensions as to accommodate a stock of cards 34 as indicated in Fig. 2 of the drawing. It will be seen that the cards may be viewed completely while supported at a convenient angle of visibility. In the event that additional cards are to be required from storage a particular shelf is drawn forwardly in the direction of the arrow a, as indicated in Fig. 3. As this takes place the compartment floor 28 is also drawn forwardly and lifted. This permits access to the compartment over the top of the back wall 30 of a shelf and beneath the floor of the shelf above it. After the merchandise has been removed the back panel 30 may be swung rearwardly, thus forcing the compartment formed by the members 27 and 28 rearwardly along the guide strips 24 so that the shelf structure will be again restored to its normal position and will be held in position until moved again.

It will thus be seen that the display rack here disclosed provides a convenient visible display for a large number of cards or other similar articles, and makes it possible for them to be observed completely without handling of the stock, at the same time providing convenient storage space for the articles on display.

While I have shown the preferred form of my invention as now known to me, it will be understood that various changes may be made in combination, construction and arrangement of parts by those skilled in the art, without departing from the spirit of my invention as claimed.

Having thus described my invention, what I claim and desire to secure by Letters Patent is:

1. A display device comprising a base structure including vertically disposed parallel side members having inclined forward edges, a plurality of shelf structures disposed between said side members and arranged at the angle of the inclination of the forward edges, said shelf structures each comprising a floor element disposed at an angle to the horizontal, a back panel extending upwardly and disposed at right angles to the floor element, the upper edge of the back panel terminating at a point beneath the forward edge of the floor element thereabove, means pivotally connecting the forward edges of the floor elements with relation to said side members, a

stop in the rear of each of said back panels limiting the rearward swinging movement of the units, a compartment disposed in the rear of each shelf unit and accessible when the shelf unit is swung forwardly upon its pivot, said compartment comprising a floor member hinged to the back panel, a back wall carried at the rear edge of the floor member, and guide means supporting the compartment thus formed whereby it may move forwardly as the shelf unit is swung upon its pivot.

2. A display device, comprising spaced vertical side walls, a plurality of display and compartment units mounted therebetween and in superposed relation to each other, said units each comprising a shelf pivotally mounted between said side walls on a horizontal axis disposed adjacent to its forward edge and having an upwardly projecting back wall cooperating with the shelf to support articles to be displayed, a storage compartment being formed in the rear of said back wall and comprising a floor member pivoted at its forward end to the back of the back wall and having an upwardly projecting rear wall at the rear and free end thereof, and guides for the free ends of said compartment floors and disposed substantially in the plane of the shelf whereby when the back wall carried by the shelf is swung forwardly from beneath the shelf disposed thereabove the compartment floor will be drawn forwardly to dispose stored articles thereon in an accessible position to be reached through the opening between the upper free end of the back wall and the shelf thereabove.

3. A display device, comprising a base structure including vertically disposed parallel side members having inclined forward edges, a plurality of shelf structures disposed between said side members and arranged at substantially the angle of the inclination of the forward edges, said shelf structures each comprising a floor element disposed at an angle to the horizontal, a back panel extending upwardly and disposed at right angles to the floor element, the upper edge of the back panel terminating at a point beneath the forward edge of the floor element thereabove, means pivotally connecting the forward edges of the floor elements with relation to said side members, a stop in the rear of each of said back panels limiting the rearward swinging movement of the units, and a compartment disposed in the rear of each shelf unit and accessible when the shelf unit is swung forwardly upon its pivot, said compartment comprising a floor member hinged to the back panel and a back wall carried at the rear edge of the floor member.

GEORGE E. BUZZA.
